DETACHABLE VEHICLE WHEEL

Charles H. Martin, Argos, Ind., assignor, by direct and mesne assignments, of one-half to H. L. Ludwig and Son, Inc., a corporation of Florida

Application August 16, 1939, Serial No. 290,517

5 Claims.

(Cl. 301—9)

This invention relates to a detachable vehicle wheel, the general object of the invention being to provide means whereby the wheel can be easily and quickly removed from the brake drum 5 and just as easily attached to the drum, by manual movement axially of a ring-shaped member, this movement of said ring-shaped member actuating the holding means which hold the wheel to the drum.

10 This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in 20 which—

Figure 1 is an elevational view with parts broken away showing a wheel assembly provided with the invention.

Figure 2 is a view approximately on the line 25 2—2 of Figure 1 with the wheel fastened to the drum.

Figure 3 is a similar view but with the wheel removed from the drum.

Figure 4 is a fragmentary sectional view 30 through the drum and showing one of the studs.

Figure 5 is a section on line 5—5 of Figure 3.

Figure 6 is a view of one of the arm members having the keyhole shaped opening therein receiving a stud.

35 In these views the letter A indicates a brake drum of a wheel and the letter W indicates a portion of the wheel. These parts are of conventional or any desired construction and in carrying out the invention I provide a plurality of studs 1 which are riveted to the drum as shown and each stud has a head 2 at its outer end and each head is provided with a pair of slots 3 therein, these slots being arranged opposite each other and are beveled, as shown at 3', with the bevel tapering toward the hub. The wheel is

40 provided with an annular part 4 which is formed with a plurality of holes 5 for receiving the heads of the studs. The annular part is formed with an axially extending flange 6 which has slots 7 therein, these slots 7 being arranged adjacent the holes 5, as shown.

A plurality of arms 8, of flat construction, are slidably arranged on the flange 4 and each arm is provided with a head 9 having a substantially 45 keyhole shaped opening 10 therein for fitting

over a stud head 2 and a reduced part 11 extends from each head 9 and slidably engages a slot 7. The enlarged part of the opening 10 is of greater area than the head of the stud so that it can pass over the head but the narrow part 5 10' of the opening will engage the slots 3 in the head, when the arm 8 is moved inwardly. When the arm is moved outwardly the shoulders 11' formed by the reduced part 11, will engage the flange 6 which limits outward movement of the 10 arm and holds the enlarged part of the opening 10 in position to receive the head 2 of a stud.

A pair of outwardly diverging springs 12 have their inner ends connected with opposite sides of 15 the intermediate part of each arm 8. The other ends of the springs are connected with the annular part 4 and these springs tend to move the arms outwardly with the shoulders 11' engaging the flange 6 and the enlarged parts of the openings 20 in position to receive the studs.

The inner end of each arm 8 is bent outwardly first at right angles to form a shoulder 8' and then at an acute angle, as shown at 13, and this bent part is formed with a longitudinally 25 extending elongated slot 14 through which passes one end of a pin 15, the other end of which has an eye 16 therein through which passes a ring member 17 which is located adjacent the outer end of the hub of the wheel when the wheel is 30 in place. A spring 18 is located on each pin and has one end bearing against a washer 19 which also bears against the bent part of the arm and the pin is held in the slot 14 of the bent part by a cotter pin 20.

The ring member 17 acts as a handle for manipulating the arms to locking and unlocking position. When the ring member 17 is moved outwardly to the position shown in Figure 3 the pins 15 will be caused to move the arms 8 outwardly to place the large parts of the openings over the heads of the studs so that the wheel can be pulled from the studs or if the wheel is already off the drum then in this position of the parts the wheel can be readily placed against the drum with the heads of the studs passing through the largest parts of the openings 10. Then the ring member 17 is forced inwardly and as this is done the pins 15 are pressed inwardly 40 to the position shown in Figure 2 and in this position of the parts the springs 18 will force the washers 19 against the shoulders 8' at the inner ends of the arms 8 so that the pressure 45 of the springs moves the arms inwardly and thus causes the small parts 10' of the openings 10 to 50 55

engage the slots 3 in the heads of the studs and thus the wheel will be locked to the drum. Due to the beveling 3' of the slots 3 of the stud heads, as parts of the arms enter the slots, the wheel parts will be caused to press firmly against the drum part to tightly hold the wheel against the drum.

In order to increase the wedging action between the heads 2 of the studs and the outer ends 10 of the arms 8 those portions of the heads 9 of the arms 8 adjacent the slots 10' are beveled, as at 10" in Figure 6. Thus the wedge or beveled face of the walls of the slots 10' together with the bevels of the slots 3 in the studs will cause the 15 wheel to be moved tightly against the drum as the arms move inwardly under the action of the springs 18 and thus the wheel is firmly locked to the drum at a plurality of points so that there is absolutely no danger of the wheel wobbling 20 and while the drawings show the studs as riveted to the drum it is to be understood that such studs will be formed with the drum when the drums are manufactured in accordance with the invention.

25 Thus the wheel is firmly connected with the drum and then when it is desired to release the wheel from the drum it is simply necessary to pull the ring member 11 outwardly to the position shown in Figure 3 to move the arms 8 outwardly so that the enlarged parts of the openings 10 will register with the heads of the studs so that the arms can be passed over the heads as the wheel is being pulled from the drum.

It is thought from the foregoing description 30 that the advantages and novel features of the invention will be readily apparent.

It is to be understood that changes may be made in the construction and in the combination and arrangement of the several parts provided 40 that such changes fall within the scope of the appended claims.

What I claim is:

1. Means for connecting a wheel part to a carrying part comprising headed studs on the carrying part, each head having oppositely arranged 45 slots therein, arms slidably carried by the wheel part and having substantially keyhole shaped openings therein, the large parts of which are of greater area than the area of the heads of the 50 studs, with the small parts of the openings having their side walls engaging the slots, when the arms are moved inwardly, a handle member, and means, including spring means, for connecting the handle member with the inner ends of the 55 arms for moving the arms outwardly, when the handle member is moved outwardly, to release the arms from the studs and when the handle member is moved inwardly the arms are moved inwardly to cause the small parts of the openings 60 to engage the slots of the heads of the studs.

2. Means for connecting a wheel part to a drum part comprising headed studs carried by the drum part, each head having a pair of diametrically arranged slots therein, a plurality of 65 arms slidably arranged on parts of the wheel part and each arm having a substantially key-hole shaped opening therein, the large part of which is of greater area than the head of a stud and the small part of which has its walls engaging the slots in said head when an arm is moved inwardly, each arm having an outwardly turned part provided with a slot, a ring member, pins having ring-shaped heads through which the ring 70 member passes, said pins having their free ends 75 passing through the slots of the arms, means for

holding said ends in said slots, springs surrounding the pins and pressing against the turned ends of the arms, when the ring member is moved inwardly to move the arms inwardly, the arms being moved outwardly by the pins when the ring member is moved outwardly. 5

3. Means for connecting a wheel part to a drum part comprising headed studs carried by the drum part, each head having a pair of diametrically arranged slots therein, a plurality of arms 10 slidably arranged on parts of the wheel part and each arm having a substantially keyhole shaped opening therein, the large part of which is of greater area than the head of a stud and the small part of which has its walls engaging the 15 slots in said head when an arm is moved inwardly, each arm having an outwardly turned part provided with a slot, a ring member, pins having ring-shaped heads through which the ring member passes, said pins having their free 20 ends passing through the slots of the arms, means for holding said ends in said slots, springs surrounding the pins and pressing against the turned ends of the arms, when the ring member is moved inwardly to move the arms inwardly, the arms 25 being moved outwardly by the pins when the ring member is moved outwardly, the slots in the heads of the studs being beveled to cause the arms to move the wheel part firmly against the drum part as the arms move into the slots. 30

4. Means for connecting a wheel part to a drum part comprising headed studs carried by the drum part, each head having a pair of diametrically arranged slots therein, a plurality of arms 35 slidably arranged on parts of the wheel part and each arm having a substantially keyhole shaped opening therein, the large part of which is of greater area than the head of a stud and the small part of which has its walls engaging the slots in said head when an arm is moved inwardly, each arm having an outwardly turned part provided with a slot, a ring member, pins having ring-shaped heads through which the ring 40 member passes, said pins having their free ends passing through the slots of the arms, means for holding said ends in said slots, springs surrounding the pins and pressing against the turned ends of the arms, when the ring member is moved inwardly, to move the arms inwardly, the pins moving the arms outwardly when the ring member is moved outwardly, spring means tending to 45 move the arms outwardly, and guiding means for the sliding movement of the arms carried by the wheel. 50

5. Means for connecting a wheel part to a carrying part comprising studs on the carrying part each having oppositely arranged slots therein, arms slidably carried by the wheel part and having substantially keyhole shaped openings therein, the large parts of which are of greater area 55 than the area of the studs, with the small parts of the openings having their side walls engaging the slots, said side walls of the small parts of the openings and the walls of the slots being beveled to provide a wedging action when the parts 60 engage, a handle member, and means for connecting the handle member with the inner ends of the arms for moving the arms outwardly when the handle member is moved outwardly to release the arms from the studs and when the handle member is moved inwardly the arms are moved inwardly to cause the walls of the small parts of the openings to engage the slots of the studs. 65
